UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

FOLDING ROLL FOR PAPER-FOLDING MACHINES.

Application filed August 8, 1922, Serial No. 580,438. Renewed September 27, 1926.

- This invention relates to a folding machine which is designed for folding the highly illustrated products from newspaper or periodical rotary presses.
- 5 The principal objects of the invention are to provide the folding rolls with means for preventing the smudging of the outside of the product and for preventing the pressing of the sheets together so as to smudge the inside of the printed products; to provide for the folding of such products by the exertion of pressure only on the longitudinal and transverse margins without bringing the inked parts of the products into firm contact with the rolls, or pressing the inked parts of the sheet together between the rolls; and still to provide for effectively and firmly creasing the fold in the product.
- 10 Reference is to be had to the accompanying drawings, in which
- 15 Fig. 1 is a diagrammatic view of a folder showing a preferred form of this invention applied thereto;
- 20 Fig. 2 is a plan of the pair of folding rolls, parts being broken away to show interior construction;
- 25 Fig. 3 is an end view of the same;
- 30 Fig. 4 is a sectional view on the line 4—4 of Fig. 2;
- 35 Fig. 5 is an end view of one of the end margin rings or nips removed from the roll;
- 40 Fig. 6 is a side view of one of the rolls; and
- 45 Fig. 7 is a view of a printed and folded product for which this invention is designed to be used.

In the folding of the highly illustrated products of newspaper or periodical rotary presses, where there is little time for the ink to dry, the products are invariably smeared or smudged with ink. This is caused by the fact that the products are folded between two rolls which bear upon the printed surface of the paper throughout. Therefore they press these partially dried printed surfaces against each other, smudging the inside of the printed product. Also, on account of the pressure of the rolls themselves, they smudge the outside of the product. This difficulty has been the subject of many inventions, several of which relate to the registering of the rolls with the products so that the smudge will al-

ways occur at the same spot or spots on the paper.

This invention is designed for providing a practical means for folding such products by contact with the longitudinal and transverse margins only and preventing the pressure of the rolls against the inked parts of the products. This also, of course, prevents the pressing of the inked parts of the sheets together by means of the rollers and thus prevents both forms of smudging above mentioned.

In Fig. 7 I have indicated a folded product of the nature referred to above, in which the heavy inked portions on the illustration will not be dry when the paper goes through the folding rolls and will transfer part of their ink to one of them, which in turn prints it back on the next following paper. The margins A and B are indicated in this figure and also an arrow is shown to indicate the direction of motion through the folding rolls.

The web which is to be folded to produce the product shown in Fig. 7 passes, as usual, through the former, the nipping rolls, between the folding cylinder 10 and cutting cylinder 11, and then between a pair of folding rolls 12. These rolls preferably are sized and timed, as has been done heretofore, so as to make a single complete revolution during the exact period of time required for the passage of a complete product through them, but the means for securing this result is not shown herein. These rolls are adjustable toward and from each other, and are set sufficiently far apart so that their normal cylindrical surfaces do not bear hard upon the sheet. In fact they do not bear upon it sufficiently to feed the sheet by their own action at the speed of the rolls.

One or both of these rolls carries a margin folding block 13. This, in each case, extends along the roll and has a convex surface preferably scored slightly or roughened sufficient to form a good feeding surface and having a curvature concentric to that of the roll on which it is carried. These blocks are mounted in radial recesses extending from one end of each roll to the other and each one is shown as having an enlargement 14 at the rear to engage a shoulder on this recess, and prevent the block

from being displaced in a radial direction. I have shown both of these blocks as provided with springs 15 behind them for holding them out in their outermost position 5 so as to contact with each other once during each revolution. It is not absolutely essential that both of these blocks have springs behind them, but one of them should. These blocks are so placed as to coincide with the 10 margin A of the sheet which they are to fold. Therefore, as they come around into contact with this margin they will feed the sheet forward positively, but will not take up any ink. The fold at the back of the 15 sheet will be firmly and sharply creased by the pressure of these blocks. After these blocks have acted they pass the printed product along. Then the rolls are out of contact with the parts of the sheet between the 20 two margins A and not constituting a part of the top and bottom margins B so that these parts will not be pressed by these rolls or by the blocks.

The side margin folding blocks above described do not act constantly on the sheet. For the purpose of providing means that will always engage the sheet and feed it along constantly, I have provided each end of the roll with a pair of studs 20. On each 30 stud is placed a rubber thimble 21 surrounding it and constituting a spring or buffer. Mounted on these thimbles at each end of the folding rolls are nipping collars 22. Each of these collars 22 has two opposite 35 perforations through it fitting the rubber thimbles 21 and it has a central opening 23 materially larger than the stud or shaft 24 of the folding roll to permit of play. The nuts and washers on the ends of the studs 20 fit freely enough so that the collar can move 40 sufficiently to give it free play.

It will be noted that the collars are located on the ends and in fact beyond the ends of the rolls and are held against the 45 ends instead of being located on the circumference. The rubber thimbles allow the collar to yield in all directions in a transverse plane about the studs 20. In this way the means for holding the collar on itself 50 acts to prevent creeping of the collars circumferentially.

The exterior cylindrical surfaces of these nipping collars are milled to provide a good gripping surface for feeding the paper. 55 These nipping collars are so located and of such width that they constantly contact with the margins B of the product, and feed the product along by that contact. On account of their being mounted on the rubber springs 60 and of the play which they have, they bear sufficiently against each other at the two ends of the folding rolls to hold the product positively between the folding rolls after the folding blocks 13 have passed, so that the 65 product is kept in motion and in time with

the rest of the machine. On account of the resilient mounting of these collars they can be displaced slightly in the operation of the folder without displacing the roll. The same is true of the folding blocks 13. Therefore products of greatly varying thicknesses can be folded by this machine without adjustments and without causing any particular strain especially on the bearings of the folding rolls. It will be seen, therefore, that 70 the printed sheets or folded products can be folded by this means in a quick and neat manner without danger of smearing the outside sheets or smutting the inside surfaces on account of the freshly inked parts being 75 pressed together by the folding rolls, yet the folding is done accurately and efficiently and the products kept in time with the apparatus so that the folding blocks 13 will always 80 register with the side margins of the various products as they come through. The folded products delivered from the rolls are laid by a fan or the like on a travelling belt 85 or delivered in any other desired way.

Although I have illustrated and described 90 only a single form of the invention, I am aware of the fact that modifications can be made therein by any person skilled in the art without departing from the scope of the invention as expressed in the claims. 95

Therefore I do not wish to be limited to all the details of construction herein shown and described, but what I do claim is:—

1. A folding and forwarding roll having a collar thereon of slightly larger diameter 100 than the roll to nip the product, and means for holding the collar at a plurality of points and allowing it to yield slightly and equally in all directions in a transverse plane around said points.

2. The combination with a pair of folding rolls for folding sheets having the main portions of their surfaces placed a slight distance apart to prevent their pressing on the sheets, with folding blocks on the rolls projecting beyond said surfaces and having roughened operative surfaces adapted to engage the sheets at predetermined points and press the sheets together at those points, and means for yieldingly forcing one of said 110 blocks toward the other.

3. The combination with a pair of folding rolls of a diameter less than that required to cause their surfaces to press against the sheets to be folded, with spring-pressed longitudinal blocks carried by said rolls projecting from said surfaces, said blocks having cylindrical exterior surfaces concentric with their respective rolls for engaging the sheets and pressing them together, the blocks 120 on the two rolls registering with each other.

4. The combination with a folding roll having a spring-pressed folding block extending longitudinally thereof for engaging the side margins of the folded sheets, with 130

yielding means at the ends of said roll for constantly pressing on the top and bottom margins and while the folded products are being fed forward at all times while the roll is rotated.

5. In a folding machine, the combination with a folding roll, of means connected with said roll for forwarding a doubled printed product between it and its complementary 10 roll and folding it without placing any printed part of the printed product under pressure, comprising a collar on the end of the roll and means for allowing the collar to yield equally in all directions in a transverse 15 plane, whereby said means itself prevents material creeping circumferentially.

6. The combination with a pair of folding rolls for folding sheets, said rolls being placed far enough apart to prevent the application of pressure by them to the printed product, of means mounted on and beyond the ends of said rolls for engaging the margins of the printed product and forwarding it positively with the rolls, and means mounted 25 on the ends of the rolls for allowing the paper engaging means to yield to permit of operation on products of different thicknesses.

7. The combination with a pair of folding

rolls, of a pair of margin nipping collars 30 at the ends of said rolls, and yielding means for supporting said collars against the flat ends of the rolls, whereby they will press on a single sheet carried between the rolls sufficiently to feed it forward or will yield 35 to permit a thick folded product to pass between the rolls.

8. As an article of manufacture a folding roll provided at the end thereof with an end margin nipping collar mounted on the roll 40 to yield in all directions.

9. As an article of manufacture, a folding roll having on the end a soft rubber thimble, and an end margin nipping collar having a 45 perforation for receiving said thimble and capable of yielding a short distance.

10. As an article of manufacture, a folding roll having on the end thereof a pair of studs, soft rubber thimbles surrounding said studs, and an end margin nipping collar 50 having two perforations for receiving said thimbles and capable of moving a short distance in all directions transverse to the axis of the roll.

In testimony whereof I have hereunto af- 55 fixed my signature.

HENRY A. WISE WOOD.
